BOX AND LID STOP

Glenn E. Stilwell, Riverside, Calif., assignor to
Food Machinery Corporation, San Jose, Calif.,
a corporation of Delaware

Application May 14, 1943, Serial No. 437,008

9 Claims. (Cl. 1—10)

This invention relates to nailing machines and particularly to such machines as are employed for applying lids to boxes.

A common type of nailing machine for lidding boxes drives all the nails in the lid at one time. To assist in locating a box in such a machine in preparation for lidding the same, stops are ordinarily provided against which the box is moved. Other stop means is also provided against which the lid may be placed to properly position this over the box. The nailing mechanism is then actuated which nails the lid onto the box.

It is an object of my invention to provide a combined stop means which will not only position the box as aforesaid, but which will also position the lid.

It has been found advantageous to incorporate in nailing machines as aforesaid some means whereby they may be adjusted for the lidding of boxes of different sizes. This introduces a problem of adapting the stop means for the box and for the lid for each readjustment of the machine to lid a different sized box.

It is an object of my invention to provide a relatively simple and easily adjustable box and lid stop means which may be incorporated in an adjustable lid nailing machine.

The manner of accomplishing the foregoing objects as well as further objects and advantages, will be made manifest in the following description taken in connection with the accompanying drawings in which:

Fig. 1 is a rear elevational view of a substantial upper portion of a nailing machine in which is incorporated a preferred embodiment of my invention, a box and lid being shown positioned in said machine in readiness for lidding.

Fig. 2 is an enlarged front three-quarters perspective view of the stop device itself of said invention.

Fig. 3 is a similar rear three-quarters perspective view of said stop device.

Fig. 4 is an enlarged cross sectional view taken on the line 4—4 of Fig. 1 with the box and lid ready for the nailing operation to start.

Fig. 5 is a detail sectional view taken on the line 5—5 of Fig. 4 and shows the box supported on the conveyor wheels above the nailing anvil.

Fig. 6 is an enlarged fragmentary operational view taken on the line 5—5 of Fig. 1 and illustrates the positions of the operative parts at the moment of the extreme downwardmost movement of the nailing means.

Fig. 7 is a view similar to Fig. 5 and illustrates

the positions of the operative parts upon the return upward of the nail driving means to its extreme upwardmost position.

Fig. 8 is a view similar to Fig. 6 and illustrates the discharge of a lidded box from the machine and the delivery of a new box to be lidded, to said machine.

Fig. 9 is an enlarged sectional view taken on the line 9—9 of Fig. 7 and illustrates the lid flushing devices just before these are brought into contact with side edges of a lid in the initial phase of a lid nailing operation.

Referring specifically to the drawings a nailing machine 10 is illustrated therein which includes 15 a frame 11 having side standards 12 joined by box support I-beam members 13 and by a base (not shown) for supporting the machine and on which is mounted a motor (not shown) for driving the machine.

20 The frame also includes a rod 14 (see Figs. 1 and 4) which is parallel with and lies between the members 13. Slideable in the inner channels of the I-beam members 13 and on the rod 14 is a pair of cross beams 20 which carry threaded conveyor-supporting posts 21, the latter being adjustable vertically on the beams 20 by manipulation of nuts 22. The beams 20 are adjustable towards and away from each other and are adapted to be held in any relation thus accomplished by 30 set screws 23 (see Fig. 4).

Mounted on the upper ends of the pair of posts 21 on each of the cross beams 20 is a conveyor track 24 having wheels 25, these tracks combining to form a two-track conveyor 26. The vertical adjustability of the posts 21 and the free lateral adjustability of the beams 20, just described, permits the two tracks 24 to be selectively located in the machine 10 for handling boxes of any size within a wide range of sizes.

40 The wheels 25 may be fixed on the tracks 24, but in each track 24 they are preferably mounted on a separate angle iron 27 which is held up by compression springs 28 applied thereto by bolts 29 which extend upwardly through the angle iron 27 and are tapped into suitable holes in the track 24.

45 Mounted on the frame 11 above the conveyor 26 is a nailing mechanism 35. This mechanism includes a nail-driving cross head 36 which is adapted to be reciprocated downwardly and upwardly by pitmans 37, the latter being actuated by the drive mechanism aforementioned which is not shown in the drawings but the construction and operation of which is well known in the art.

50

The cross head 36 carries rods 38 which are vertically slideable therein and have guides 39 at their lower ends which are guided on the frame side standards 12 during reciprocation of the cross head 36. Adjustably mounted on the cross head 36 and extending vertically downwardly therefrom are nail drivers 40.

Mounted on the guides 39 is a rectangular nail chuck-supporting frame 50 having clamp rails 51 formed along its front and rear edges for supporting clamps 52 each pair of which is adapted to adjustably support on the frame 50 a pair of chuck mounting bars 53. Mounted between the bars of each of these pairs is a row of nail chucks 58 one of the drivers 40 being slideably disposed in each of these chucks. Nails are adapted to be delivered to the several chucks 58 through flexible tubes 59 which are supported on the frame 50 by brackets 60. Nails are delivered to the upper ends of the tubes 59 by a nail picking mechanism (not shown) which is supported on the top of the frame 11, the construction and operation of this being well known in the art.

Each of the chucks 58 is preferably provided with a side lid flusher 65 which is pivotally mounted on the chuck as shown in Fig. 9 in an adjustable position determined by a set screw 66 and yieldably held inward against this chuck by a spring 67.

Slideably mounted between the bars 53 of each of the pairs of these carried by the frame 50 is a stop mechanism 70. Each of these mechanisms 70 includes a body 71 having notches 72 and clamps 73 adjacent its upper end for adjustably securing the mechanism in a desired adjusted position on the bars 53 with which the mechanism is associated.

The body 71 has a channel 74 covered by a plate 75 and has ears 76 extending rearwardly from the lower end thereof. The body also has provided therein front and rear spring mounting pins 77 and 78.

Vertically slideable in the channel 74 is a box and lid stop 80 having a stop shoulder 81 at its upper end and a stop pin 82 near its lower end to limit its vertical movement in the channel 74. A pin 83 provided in the shoulder 81 is connected to the pin 77 by a contractile spring 84 so as to yieldably urge the stop 80 towards its downward-most position in the body 71 as shown in Figs. 2 and 3. The lower end of the stop 80 is provided with a rearwardly disposed cam face 85 and each of the stops has mounted thereon at its lower end a roller 86, this roller on each of the stops 80 being preferably disposed inwardly towards the middle of the machine 10.

Pivoted at its upper end between the ears 76 and yieldably held inwardly by a contractile spring 90 connected to the pin 78 is a latch 91 the lower end of which has a latch shoulder 92 which is rounded to ride over the cam face 85 on the lower end of the stop 80 and to be pulled inwardly beneath this stop by the spring 90 when the stop slides upwardly in the channel 74 a sufficient distance to permit this.

Operation

The adjustability of the conveyor 26 and the nailing mechanism 35 of the machine 10 adapt this for lidding boxes of a wide variety of sizes.

For illustrative purposes the machine is shown in the drawings as when lidding a box B by nailing a lid L on this box. Before undertaking to lid a box of this size or of any other size the tracks 24 of the conveyor 26 must be positioned so that they

are at the right height to support this box so that when the nailing mechanism 35 is at the bottom of its reciprocatory movement the drivers 40 just drive the nails flush with the top of the lid on the box. The tracks 24 are also adjusted in position to properly guide and support the box with the latter centrally disposed in the machine as shown in Fig. 1.

In thus adjusting the machine 10 the clamps 52 must be located to properly space the chucks 58 so that in the nailing operations these chucks will drive the nails where it is desired that these be located.

Finally, the box and lid stop mechanisms 70 of my invention must be properly positioned on the bars 53 to stop each box when it is placed in the machine and each lid when it is placed on top of this box so that when the nailing mechanism moves downwardly the lid will be properly nailed onto the box. This adjustment of the stop mechanism is readily accomplished by a manipulation of the clamps 73.

When the machine 10 is thus adjusted as for lidding a box B one of these boxes is fed into the machine as shown in Fig. 4, by pushing this along the conveyor 26 until the rear upper corners of this box contact the lower ends of the stops 80. A lid L is then pressed into place over this box B until the lid also engages these stops as shown in Fig. 4. The drive mechanism (not shown) is now actuated so as to cause a vertical reciprocation of the nailing mechanism 35 relative to the conveyor 26. As the downward movement of the nailing mechanism starts, the flushers 65 (see Fig. 9), move into contact with side edges of the lid 12 and shift this into a position in which its edges are flush with the sides and ends of the box B, and retains the lid in this position until the chucks 58 come downwardly on the lid and the drivers 40 drive the nails from the chucks through the lid and into the box B as shown in Fig. 6.

Being fixed upon bars 53 the body 71 of each of the stop mechanisms 70 travels downwardly and upwardly with these bars in the reciprocatory motion of the nailing mechanism. Being slideable in the channels 74, however, the stops 80 respond to contact of the pins 82 with the lid L to slide upwardly relative to the bodies 71 as shown in Fig. 6. Here it is seen that the shoulders 92 of the latches 91 of the stop mechanism 70 are pulled inwardly by the springs 90 beneath the lower ends of the stops 80 so that when the nailing mechanism returns upwardly in the second half of its reciprocatory motion the stops 80 are lifted above the lid L of the lidded box B as shown in Fig. 7.

After box B has thus been lidded and the nailing mechanism 35 is returned to its uppermost position as shown in Fig. 7, the box is free to be discharged from the machine 10 onto a conveyor 95 provided to receive it. When thus being discharged the lidded box B strikes the lower ends of the latches 91 so as to shift these out from under the stops 80. This permits these stops to be urged downwardly by their springs 84 to bring the stop rollers 86 into contact with the top of the lid L.

When the lidded box B passes out from under the stops 80 these are returned to their downwardmost position by the springs 84 as shown in Fig. 8, in readiness to halt and properly position for lidding a new box C which is introduced into the machine as shown in Fig. 8, following the lidding of box B. The box B, of course, continues out from under the latches 91 so that these are returned by their springs 90 into their normal

position contacting the cam faces 85 of the stops 80 as shown in Figs. 1, 2, 3 and 4.

From the foregoing description it is believed manifest that my invention has numerous advantages. It provides an inexpensive and efficient stop means for both a box and a lid in a lid nailing machine. The stop mechanism of my invention is particularly useful where the lidding machine is adjustable to handle boxes of different sizes as the expansion of the machine to fit these boxes carries the stop mechanism right with it, so that this is always properly related to the boxes with a minimum of adjustment being required to take care of the stops.

What I claim is:

1. In a machine for working on boxes, the combination of: a support means for receiving a box; overhead means disposed above said support means; stop means provided on said overhead means and extending downwardly therefrom into a path along which a box delivered into said machine is adapted to be discharged, said stop means halting said box in a proper position to be worked upon; means causing relative reciprocatory movement between said support means and said overhead means to perform an operation on said box; means responsive to said reciprocatory movement to withhold said stop means from said path thereby permitting said box when it is started along said path following said operation to bypass said stop means; and release means extending into said path so as to be engaged by said box to release said stop means and permit the latter to return into said path after the discharge of said box from said machine.

2. In a machine for working on boxes, the combination of: a support means for receiving a box; overhead means disposed above said support means; stop means provided on said overhead means and extending downwardly therefrom into a path along which a box delivered into said machine is adapted to be discharged, said stop means halting said box in a proper position to be worked upon, said stop means being vertically slideable on said overhead means; means causing relative reciprocatory movement between said support means and said overhead means to perform an operation on said box; means on said stop means engaged by said box during said reciprocatory movement to cause relative sliding movement between said stop means and said overhead means during the initial half of said reciprocatory movement; and latch means for preventing a return movement of said stop means relative to said overhead means during the second half of said reciprocatory movement to cause said stop means to be disposed out of said path thereby permitting said box to be discharged from said machine along said path.

3. In a machine for working on boxes, the combination of: a support means for receiving a box; overhead means disposed above said support means; stop means provided on said overhead means and extending downwardly therefrom into a path along which a box delivered into said machine is adapted to be discharged, said stop means halting said box in a proper position to be worked upon, said stop means being vertically slideable on said overhead means; means causing relative reciprocatory movement between said support means and said overhead means to perform an operation on said box; means on said stop means engaged by said box during said reciprocatory movement to cause relative sliding movement between said stop means and said overhead means

during the initial half of said reciprocatory movement; and latch means for preventing a return movement of said stop means relative to said overhead means during the second half of said reciprocatory movement to cause said stop means to be disposed out of said path thereby permitting said box to be discharged from said machine along said path, said latch means extending into said path so as to be engaged by said box when the latter is discharged from said machine along said path to free said stop means and allow the latter to return into said path to stop the next box delivered to said machine in proper position to be worked upon.

4. In a lidder the combination of: support means for receiving a box; overhead means; means causing relative vertical movement between said overhead means and said support means to bring said overhead means against a lid disposed over said box to press said lid against said box; stop means vertically slideable on said overhead means and normally disposed to stop a box and a lid therefor in said lidder in proper position for lidding said box; and means mounted on said overhead means for engaging said stop means during relative vertical movement between said support means and overhead means incidental to a lidding operation to withdraw said stop means from the position in which it would intercept the discharge of the lidded box in the same direction in which said box was moved against said stop means.

5. In a machine for working on boxes, the combination of: a support means for receiving a box; overhead means disposed above said support means; stop means provided on said overhead means and extending downwardly therefrom into the path of a box delivered into said machine, to stop said box in a proper position to be worked upon; means causing relative reciprocatory movement between said support means and said overhead means to perform an operation on said box; means adapted to cooperate with a box in said machine to cause relative vertical movement between said stop means and said overhead means during the initial half of said reciprocatory movement; and means for preventing relative vertical movement between said stop means and said overhead means during the second half of said reciprocatory movement to cause said stop means to be disposed out of the path of said box to permit the resumption of movement of said box in the same direction in which it was moved against said stop means.

6. In a nailing machine for lidding boxes, the combination of: a frame; box support means on said frame; a nailing mechanism disposed above said support means and adapted to nail a lid on a box resting on said support means, said mechanism including a head carrying two pairs of spaced bars, a set of nail chucks adjustably mounted between the bars of each of said pairs; two stops, one of which is adjustably mounted between the bars of each of said pairs, said stops extending downwardly a sufficient distance to engage and properly position in said machine a box and a lid for the lidding of said box; and means for causing relative reciprocatory movement between said support means and said nailing mechanism to drive nails from said chucks through said lid and into said box.

7. A combination as in claim 6 in which said stops when positioning a box and lid as aforesaid, extend into a path along which said box is adapted to be discharged from said machine after

being lidded; and means responsive to said reciprocatory movement for withholding said stops from said path to permit the discharge of said box from said machine.

8. In a nailing machine for lidding boxes, the combination of: a frame; a two-track box conveyer for supporting boxes in said machine; a nailing mechanism disposed above said conveyer, said mechanism including a head carrying two gangs of nail chucks, and two stops one of which is assembled with each of said gangs, the chucks and stop in each gang being adjustably spaced from each other, the spacing of said gangs and stops on said head being also adjustable, and a driver crosshead carrying drivers which are adjustably positioned thereon for driving nails from said chucks, said stops extending downwardly into the path of a box resting on said conveyer and along which said box is adapted to be discharged after being lidded; means for causing relative reciprocatory movement between said conveyer and said nail mechanism to drive nails from said chucks through said lid and into said box; and means responsive to said reciprocatory movement to withhold said stops from said path and permit the discharge of the lidded box along said path.

9. In a nailing machine for lidding boxes, the

combination of: a frame; a two-track box conveyer for supporting boxes in said machine; a nailing mechanism disposed above said conveyer, said mechanism including a head carrying two gangs of nail chucks, and two stops one of which is assembled with each of said gangs, the chucks and the stop in each gang being adjustably spaced from each other, the spacing of said gangs and said stops on said head being also adjustable, 5 and a driver crosshead carrying drivers which are adjustably positioned thereon for driving nails from said chucks, said stops extending downwardly into the path of a box resting on said conveyer and along which said box is adapted to be discharged after being lidded; means for causing relative reciprocatory movement between said conveyer and said nail mechanism to drive nails from said chucks through said lid and into said box; means responsive to said reciprocatory 10 movement to withhold said stops from said path and permit the discharge of the lidded box along said path; and means responsive to the discharge of said lidded box to release said stops from said withholding means, thereby permitting said stops 15 to return into said path to properly position the next box and lid delivered to the said machine 20 to be lidded.

GLENN E. STILWELL.
